UNITED STATES PATENT OFFICE.

HARRY C. SCHICK, OF NEWARK, NEW JERSEY.

DESIGN FOR A CATCH FOR NECKLACES.

Application filed February 7, 1923. Serial No. 5,102. Term of patent 3½ years.

To all whom it may concern:

Be it known that I, HARRY C. SCHICK, a citizen of the United States, residing at Newark, in the county of Essex and State of New Jersey, have invented a new, original, and ornamental Design for a Catch for Necklaces, of which the following is a specification, reference being had to the accompanying drawing, forming a part thereof.

The invention is clearly illustrated in the accompanying drawing, which shows my new, original and ornamental design for a

catch for necklaces, and in which Figure 1 is a front face view; Figure 2 a rear face view; and Figure 3 a side-edge view of the same.

I claim:—

The ornamental design for a catch for necklaces, as shown.

HARRY C. SCHICK.
